[57] CLAIM

The ornamental design for a pendant, as shown and
described.

DESCRIPTION

FIG. 1 is a front elevational view of a pendant showing
my new design, the broken line showing of a necklace
and legible matter is for illustrative purposes only and
forms no part of the claimed design;
FIG. 2 is a side elevational view; and
FIG. 3 is a rear view.

FIG.1

FIG.2

FIG.3
